(57) **CLAIM**

The ornamental design for a powder sifter, as shown and described.

DESCRIPTION

FIG. 1 is a top, front, left side perspective view of a powder sifter according to our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom, front, right side view thereof.

The dash-dash broken lines illustrate portions of the powder sifter that form no part of the claimed design. The dot-dash broken lines represent boundaries of the claimed design and form no part of the claimed design.

The diagonal shading represents a transparent or translucent appearance.

1 Claim, 8 Drawing Sheets
